ATTORNEY

UNITED STATES PATENT OFFICE

CHARLES L. JONES, OF PITTSBURGH, PENNSYLVANIA, ASSIGNOR TO DRYICE CORPORATION OF AMERICA, OF NEW YORK, N. Y., A CORPORATION OF DELAWARE

APPARATUS FOR AND METHOD OF FREEZING CARBON DIOXIDE

Application filed March 13, 1929. Serial No. 346,546.

My present invention relates to the making of solid carbon dioxide from carbon dioxide liquid, by expansion and gasification of part of the liquid to freeze and solidify the remainder. It was primarily designed for operation by discharging the liquid through a constricted expanding nozzle releasing the pressure and permitting expansion far below the triple point for carbon dioxide, which is approximately 75 pounds per square inch. It will be obvious, however, that various features of my invention and in fact the specific apparatus without change may be used for solidifying the liquid by operation of the expansion jet near the triple point or above it, or alternately above and below it and also for the production of relatively large carbon dioxide crystals by first maintaining pressure and temperature above the triple point to deposit liquid in the apparatus and thereafter reducing the pressure to evaporate part of the liquid as gas and to crystallize the remainder.

For all of these uses, an object of the invention is to provide a container of substantial capacity, that is liquid-tight and gas-tight, up to a desired level, above which level provision is made for escape of the gas, preferably through a screen adapted to retain snow, when the expansion jet is operated as a snow making jet.

One object of my invention is to utilize the insulating values of the cold gas produced by evaporation in the solidifying process by using it as an insulating and refrigerating jacket between the inner shell or container for the solid carbon dioxide and the wall of an outer enclosing casing, which will be designed and constructed of strength sufficient for the desired internal pressures and which for operations above the triple point and preferably also for operation below the triple point, may be 300 pounds per square inch, to afford a desired margin of safety.

In snow making apparatus of a conventional type, removal of the snow from the snow chamber has been effected either by causing the snow to pass directly into a press, which involves peculiar complications and difficulties, or by the more primitive method which

consists in temporarily stopping the process and digging out the snow from the chamber through a removable closure provided at the bottom thereof.

In all such apparatus the solid carbon dioxide adheres firmly to the inner wall of the container in which it is deposited, and has to be scraped or melted therefrom under conditions involving considerable waste. Moreover, when the manhole or closure at the lower end of the chamber is open, a heavier than air carbon dioxide gas flows out and warmer air balloons into the chamber, sublimating and wasting the snow or crystals at the center of the mass but, for the most part not reaching the solid which is clinging to the sides of the wall, the latter being ultimately freed mainly by heat conducted inward and warming up the walls of the apparatus. If the moist air does come in contact with the inner surface of the shell, it deposits water in the form of frost, thereby contaminating the product and rendering it still more difficult to clean said walls. Moreover, the entire shell is warmed up and must be recooled at great expense of liquid before the solidifying process can be restarted.

To obviate these difficulties, I arrange the manhole in the top of the chamber so that the heavy gas, instead of flowing out is held by gravity within the chamber, and employ an inner can or shell as the solidifying chamber which can be bodily withdrawn through the top of the casing when the manhole cover is removed. The can itself is of approximately the same diameter as the opening in the top of the casing and as it is lifted out through the opening, the warm air warming the relatively thin wall of the can quickly sublimates the negligible amount of solid CO₂ required to free it from the can, with but little effect on the frozen mass.

The removal of the solid in its container and replacing it or substituting a new one may be accomplished so quickly that the casing and gas therein heats up very little and air is practically all kept out or driven out by the heavy cold gas which has no opportunity to spill out of the casing.

The removable cans or shells in which the

snow is formed are preferably provided near their upper ends with vent openings permitting the CO₂ gas generated in the solidifying process to escape into the space between the shell and the casing. Where snow is to be made, these gas vents are rendered substantially impervious to the passage of snow by the provision of a screen, preferably carried by the casing and fitting snugly against the vented upper portion of the can in such a way as not to interfere with removal of the latter.

The above and other features of my invention may be more fully understood from the following description in connection with the accompanying drawing, in which

Fig. 1 is a view mainly in vertical section through a snow making apparatus embodying the invention;

Fig. 2 is a transverse sectional view therethrough on the line 2—2 of Fig. 1; and

Fig. 3 is an enlarged vertical sectional detail showing the screen and the manner of supporting it.

The solidifying apparatus and connections has been shown more or less diagrammatically indicated, and it will be understood that the chamber or casing including cylindrical body 10, convex upper and lower heads 11 and 12 and manhole cover 13 may be externally lagged with insulating material.

The manhole in the upper head 11 has an annular frame member which includes an upstanding flange portion 16 snugly fitting within the opening 17 in the tank top and the laterally and downwardly flaring flange portion 18 lying under the head 11 and welded or otherwise secured thereto. This frame ring also provides an inwardly presented annular ledge member 19 upon which a band 20 surrounding the mouth of the can 14 is adapted to seat.

The inlet for the liquid carbon dioxide, shown as a snow making nozzle 15, is preferably carried by the plate 13 and is detachably connected in any convenient or conventional manner to a supply line for the liquid CO₂, this connection being uncoupled at times when the closure 13 must be removed to permit bodily removal of the can 14 and its solidified content.

The means for tightly sealing the cover 13 in place includes clamping elements 21 removably mounted on bolts 22 fixed within bosses 23 on the head 11. Clamping members 21 are formed firmly home against the edges of the cover 13 by tightening nuts 24 on the upper exposed threaded ends of the bolts 22. Cover 13 is preferably flanged at 13a so that it snugly embraces the flange 16 as well as seating on it, it being understood that any suitable packing or gasket material may be used at this point.

The container 14 which I have arbitrarily called a can, is a relatively capacious cylin-

drical formation open at its top and near its upper end being provided with a series of relatively large gas escape openings 25. When used for snow making, these openings are firmly backed by a cylindrical screen 26. This may include a central layer 26a of fabric and inner and outer layers 26b and 26c of wire mesh.

The screen 26 is adapted to encircle and snugly fit the can 14. While it may be made bodily removable with the can, I prefer to make it as a separate unit which is permanently supported within the casing tank 10 and so positioned that when the can is slipped home, the screen backs all of the gas outlet openings 25 in the upper end of the tank. To retain this screen in proper shape and to reinforce it, the upper and lower edges of the screen may be turned outwardly and secured by substantial ring members 27, respectively secured to the frame ring 18, 18 and to a sectional annulus 28 of angle iron, the latter being suspended by hanger bolts 29 from said frame ring.

When the can and the closure 13 are in place, the liquid carbon dioxide is discharged from the nozzle 15 and the valve α adjusted to give the desired back pressure. If this is below the triple point or, say, 10 pounds above atmosphere, the liquid projected from the expansion nozzle 15, partially crystallizes into snow and partially gasifies, the snow collecting in the can 14 and the intensely cold gas escaping through the openings 25 and through the screen 26 and flowing in the space between the tank and the can 14 where it provides an effective gas film insulation which aids to prevent sublimation of the snow which has deposited in the can.

If the back pressure is above the triple point, say 80 to 150 pounds, the liquid will flow to the bottom of the can, without formation of snow but a small part of it will evaporate sufficiently to maintain liquefying temperature for the rest of it. Then the supply of liquid will be cut off and the valve α adjusted so as to permit any desired rate of boiling, thereby freezing to crystal form the remainder of the liquid. This operation may be repeated, if desired, to deposit the required amount of crystals.

In either case, when the can has been substantially filled, the supply line of liquid CO₂ is cut off, the nozzle 15 disconnected from the supply line, nuts 24 unscrewed, clamps 21 removed or swung out of the way, cover 13 carrying the nozzle lifting off, and the can 14 with its solidified content removed and the same or another can inserted.

As the can is lifted clear of the opening, there may be some slight tendency for the air to flow downwardly into the casing, but this warm air stays on top and by sublimating the remnant particles of the solid, will generate sufficient carbon dioxide gas to expel it.

Considered in its broader aspects, the device of the present invention is of considerable utility even if the container 14 is not removable, because the manhole being at the top instead of at the bottom, is accessible for removal of snow without admitting much air. Moreover, if the can is fixed, the entire device may be turned upside down and so used would not sacrifice all of its advantages.

The container 14 has been referred to throughout as a can simply for convenience of description, but it may be of various materials, and even fabric, and of any size and cross sectional shape to suit the requirements of the trade or the special circumstances of various snow making plants.

I claim:

1. An apparatus for solidifying carbon dioxide, including a chamber constructed to withstand internal pressures greater than 75 pounds per square inch, having an opening whereby it is accessible only through the top, a closure for said opening and means adapted to discharge liquid carbon dioxide into the chamber and conduit for escape of gas, said conduit being formed or provided with means for imposing desired back pressure in said chamber.

2. A carbon dioxide snow making machine, including a chamber having an opening therein, a closure hermetically sealing said opening, a snow container mounted within the chamber and removable through the opening, said closure sealing both the chamber and snow container from the exterior, a nozzle adapted to jet liquid carbon dioxide into the container to produce carbon dioxide snow and gas, and means for discharging the gas from the container through the interspace between the chamber and the container.

3. A carbon dioxide snow making machine, including a chamber having an opening therein, a closure for said opening, a snow container mounted within the chamber and removable through the opening, a nozzle adapted to jet liquid carbon dioxide into the container to produce carbon dioxide snow and gas, and means permitting the escape of the gas from the container, and preventing the escape of snow therefrom, said means comprising a screen encircling the container and snugly fitting an apertured portion thereof.

4. A carbon dioxide solidifying apparatus, including a chamber having an opening in its top, a closure hermetically sealing said opening, a receptacle for the solid insertable through the opening and depending into the chamber, said closure sealing both the chamber and snow container from the exterior, an expansion nozzle for discharging liquid carbon dioxide downward for expansion in the receptacle, said receptacle having high level openings for escape of gas laterally through said chamber.

5. A carbon dioxide expansion apparatus,

including a chamber having an opening in its top, a closure for said opening, a receptacle insertable through the opening, and depending into the chamber, an expansion nozzle for discharging a stream of liquid carbon dioxide into the receptacle, the lower portion of said receptacle being gas tight and the upper portion having openings through which gas generated by the expansion is adapted to escape, and means to prevent the escape of solid particles from said openings, comprising a screen encircling the receptacle and backing said openings.

6. A carbon dioxide expansion apparatus, including a chamber having an opening in its top, a closure for said opening, a receptacle insertable through the opening, and depending into the chamber, an expansion nozzle for discharging a stream of liquid carbon dioxide into the receptacle, the lower portion of said receptacle being gas tight and the upper portion having openings through which gas generated by the expansion is adapted to escape, and means to prevent the escape of solid particles from said openings, comprising a screen encircling the receptacle and backing said openings, said screen comprising alternate layers of fabric and fine wire mesh.

7. Apparatus as described in claim 5 and wherein both screen and container are of cylindrical formation and the screen is supported on hanger means secured to the top of the chamber.

8. A method of making solid carbon dioxide which includes enclosing a vented container in a gas-tight container, expanding liquid carbon dioxide into said vented container against an internal back pressure greater than 75 pounds per square inch, then venting gas to reduce said back pressure to boil said liquid at the triple point, thereby crystallizing part of it, then removing said vented container and contents.

9. A method of making solid carbon dioxide which includes charging liquid carbon dioxide into a container against an internal back pressure greater than 75 pounds per square inch, then venting gas to reduce said back pressure to boil said liquid at the triple point, thereby crystallizing part of it.

10. A method of making solid carbon dioxide which includes charging liquid carbon dioxide into a container against an internal back pressure greater than 75 pounds per square inch, then venting gas to reduce said back pressure to boil said liquid at the triple point, thereby crystallizing part of it at a relatively slow rate.

11. A method of making solid carbon dioxide which includes charging liquid carbon dioxide into a water tight container against an internal back pressure greater than 75 pounds per square inch, then venting gas to reduce said back pressure to boil said liquid.

at the triple point, thereby crystallizing part of it.

12. A method of making solid carbon dioxide which includes charging liquid carbon dioxide into a water tight container against an internal back pressure greater than 75 pounds per square inch, then venting gas to reduce said back pressure to boil said liquid at the triple point, thereby crystallizing part of it at a relatively slow rate.

16. Signed at New York in the county of New York, and State of New York this 12th day of March, A. D. 1929.
